SORTING MACHINE

Michael Maul, Berlin-Johannisthal, Germany, assignor to the firm Deutsche Hollerith Maschinen Gesellschaft m. b. H., Berlin-Lichterfelde, Germany

Application September 16, 1939, Serial No. 295,227
In Germany October 8, 1938

3 Claims. (Cl. 209—110)

This invention relates to sorting machines and particularly to the type in which perforated record cards are analyzed and selectively disposed into sorting pockets in accordance with the analysis. 5 By such sorting operations each sorting pocket receives a series of records bearing the same control designation.

In one form of sorting machine the machine has been equipped with sorting pockets which are commensurate in number to the control designations. In this form of machine the control designations usually consist of digit representing perforations representing 0-9, 11, and 12 and for 10 sorting records according to these designations thirteen sorting pockets have been found to be desirable, one of such pockets being a reject pocket.

In another type of sorting machine records bearing alphabetical designations as well as numerical designations are utilized to control sorting operations and instead of utilizing one sorting pocket for each control designation, sorting operations are effected in a plurality of sorting runs. 20

This type of machine is exemplified in the patent to Ford, No. 1,946,904. As described in this patent, the control records to be sorted represent twenty-six letters and ten numerals and sorting operations for records so designated are effected in a plurality of sorting runs. In one sorting run 25 the records representing numerals are sorted, and in successive sorting runs records representing the letters are sorted, divided into two runs by the letters A-M, and by the letters N-Z.

The sorting mechanism has, in such types of machines, been conditioned to be responsive to the different sets of designations by a selector, set-table to different positions. At the termination of each sorting run the pockets have received records bearing related designations, and obviously for 30 different sorting runs each pocket will receive a series of records differently designated.

It is at times desirable that the operator know for purposes of selection in which pocket records having particular designations are sorted during a sorting run, and this has, heretofore, been accomplished by labeling each pocket with all the designations of the records received therein. Since each pocket has associated therewith a plurality of characters, the operator will be required 35 to determine the position of the selector and select a designation of the group pertaining to the sorting run. This interpretation has led to errors and it is the object of the present invention to eliminate such errors by providing an improved form of indicating mechanism which will quickly give the operator the desired information.

The main object of the present invention is to provide an indicator which renders visible to the operator only the characters or designations which

are to control sorting operations during each sorting run.

A still further object of the invention is to provide such characters adjacent the related pockets so that the characters or designations brought 5 into view are intimately associated with the related pockets.

In the preferred embodiment the object of the invention is attained by the provision of an indicator bar or plate carrying groups of characters, 10 or indications, one group for each pocket and having a pointer, or window, associated with each group so that only one character or indication is visible at a time. Preferably, the indicator bar is movable and set by the adjustment of the selector. 15 In each position of the selector, for each sorting run, the indicator bar is positioned to bring into view a series of characters or indications, visible through the respective windows, and those brought into view being associated with the related pockets. 20

An indicator bar, or plate, is preferably utilized, so that they may be made up to represent the indications desired. The indications or characters may vary with the use of the machine, or the accounting system in which the sorting machine is utilized, and the provision of separate bars is preferable so that different indicator bars may be on hand to meet the different uses or requirements of the machine. 25

Other objects of the invention will be pointed out in the following description and claims and illustrated in the accompanying drawings, which disclose, by way of example, the principle of the invention and the best mode, which has been contemplated, of applying that principle. 30

In the accompanying drawings:

Fig. 1 is an illustration of a form of record card capable of being sorted by the sorting machine and shows a record card divided into two card fields, or record decks. The upper card field contains perforations representing a name and address, while the lower card field carries perforations representing associated numerical data. 40

Fig. 2 is a diagrammatic view showing thirteen sorting pockets with which the machine is preferably equipped. Vertically arranged above each sorting pocket are characters representing the designations on the records sorted in each pocket. The horizontal rows of characters represent the 45 designations of the records sorted in each sorting run. 50

Fig. 3 is a representation of the code of perforations for representing all of the digits and all of the alphabetical characters. 55

Fig. 4 is a view in side elevation, on a reduced scale, showing the general arrangement of the sorting pockets.

Fig. 5 is a fragmentary longitudinal sectional view of the sorting machine showing the parts 60

necessary for an understanding of the present invention.

Fig. 6 is a representation of an indicator bar, or plate, showing the different groups of characters associated with each of the sorting pockets.

Fig. 7 is an electrical wiring diagram of the machine.

The selection of a card field or record deck is effected by means of a selector 63 shown in Fig. 4, the function of which will be subsequently described in detail. By the positioning of the selector 63 either of the card fields may be selected for sorting operations.

Upon the selection of a particular card field for controlling sorting operations a certain column must be selected and this is preferably accomplished in a manner which is well known. The analyzing brushes are supported by a carrier 23 through which a worm screw 24 passes. The carrier 23 is adjustable transversely of the card by means of a crank handle 28, shown in Fig. 4, and which rotates the worm screw 24. The analysis of the selected card field is effected by the concurrent analysis of the perforations in a selected card column and in the present arrangement six analyzing brushes are provided for analyzing the alphabetical representing perforations in the upper card field, while for analyzing the numerical representing perforations in the lower card field only four of the analyzing brushes are utilized.

The power for driving different parts of the sorting machine is derived from a motor 20, shown in Fig. 5. The cards to be sorted are fed singly from a supply stack by means of a card picker 21 and the latter being actuated by the motor 20 feeds the card to the first set of several sets of feeding rollers 22 also driven by motor 20. When the record card to be sorted emerges from the supply stack it is received by the first set of rollers 22 which then convey the card to be sorted to the analyzing brushes 24. From the analyzing brushes a set of card feed rollers 22 feed the record card for operative correlation with a series of sorting blades 26 which are selectively adjusted under control of a magnet 27. The sorting mechanism is of a well known construction and details of its construction and operation need not be given herein. For a general understanding of the operation of the sorting mechanism it is explained that the records to be sorted are fed beneath the staggered ends of a series of sorting blades 26. At the time the record to be sorted is in operative relationship with certain sorting blades the magnet 27 is energized under control of the preceding analysis of the record. Certain of the sorting blades will be held up by the record card and the remaining sorting blades will be lowered under control of and by the energization of the sorting magnet 27. This will effect an opening between certain sorting blades and the record will then be conveyed by the feeding rollers to the selected sorting pocket.

The machine includes an adjustment whereby during each of the sorting runs records bearing certain designations will be sorted out and the remaining records will be disposed into the reject pocket "R", shown in Fig. 4. This adjustment is effected by means of a knob 33 which has, as shown in Fig. 5, three different positions. In the position shown in Fig. 5, the sorting mechanism is responsive to records bearing the digits 0 to 9 and upon the occurrence of such records they will be selectively disposed in the related sorting

pockets. In the next adjustment of the knob 33, records bearing the alphabetical designations A-M will be sorted out and, in the third, or final adjustment of the sorting knob 33, records bearing the designation N-Z will be sorted out. As is best shown in Figs. 5 and 7, the knob 33 has secured thereto a double contact arm 34, one arm of which is in continuous electrical contact with a segment 35, and which arm may be brought selectively into contact with one of a series of contact elements 36, 37, and 38. The last named contact elements are selectively connected to the translator through the associated impulse emitters in such a manner, as will be explained later, that different designations may control sorting operations during the different sorting runs.

Obviously, in the present arrangement, the knob 33 is adapted to effect a change in the control of the sorting mechanism by a different set of designations. It should be understood, however, that this arrangement is merely illustrative and other arrangements may be provided so that in other types of sorting machines the sorting mechanism will be responsive to different sets of designations in successive sorting runs.

From what has been described, it will now be apparent that each sorting pocket will receive records of different designations during different sorting runs. It is at times desirable that the operator be informed of the particular pockets receiving the differently designated records and which are sorted into the different sorting pockets during the sorting runs, and the arrangement now to be described is preferably utilized to effect this result. As best shown in Fig. 5, it will be seen that for two of the sorting pockets and in proximity thereto there is represented a plurality of characters. For example, in Fig. 5, one of the sorting pockets has the associated characters 9MZ. This indicates that this particular pocket receives records bearing similar designations during three different sorting runs. The remaining sorting pockets also have associated therewith other characters and these are arranged in accordance with the vertical groups of characters shown in Fig. 2, associated with each sorting pocket.

In order that the operator may know where the record bearing a particular designation is sorted during a sorting run an indicator bar or plate 31 is arranged beneath a cover plate 30 which has 13 apertures, or windows, designated by reference numeral 40 in Fig. 5. The indicator plate carries as shown in Fig. 6, groups of characters, preferably engraved thereon. Obviously, in accordance with the different adjustments of the indicator plate 31, only one of a group of characters associated with each pocket will be visible through each aperture, or window 40.

To effect the desired adjustment of the indicator bar or plate 31 by means of the knob 33 there is provided a pin and slot connection between the lower arm of the arm 34 and the indicator plate 31. A spring pressed plate 32 is provided to align plate 31 in its adjusted position.

With the knob 33 in the position shown in Fig. 5, it will be evident that the machine will be conditioned for a sorting run in which records bearing all of the digits 0-9 will be sorted out, and there will be visible to the operator, as shown in Fig. 4, the digits 0 to 9 on the indicator plate 31, each adjacent the pocket receiving a record similarly designated. The operator may, therefore, quickly perceive into which sorting pocket each of the differently designated records

are received. When the knob 33 is adjusted for the next sorting run, or for sorting out records bearing designations A-M, the corresponding letters on the indicator plate 31 will be visible through the apertures 40 and such characters will be associated with the respective sorting pockets. In the same manner the designations N-Z, employed for sorting operations during the third sorting run, will be visible to the operator by a corresponding adjustment of the indicator plate 31.

The operation of the machine will now be explained in connection with the electrical wiring diagram shown in Fig. 7. As previously stated, the card field selector switch 63 is positioned in accordance with the card field which is to control sorting operations. It will be seen that the switch 63 may be positioned so as to selectively connect cam controlled contacts 64a or 64b in circuit connection with a contact plate 61, the circuit to the contact plate 61 being closed through the usual card lever contacts 62. The cam controlled contacts 64a are timed so as to close one line side 70 to the contact plate 61 when the lower card field is coordinated with the analyzing brushes 24 while the cam controlled contacts 64b are timed to close at the time the analyzing brushes 24 are operatively associated with the lower card field. This will cause the concurrent analysis of the perforations of the selected card field in a selected card column and by suitable wire connections from the brushes 24 to translator magnets 50, which are connected to the other line side 80, these magnets will be energized in combination depending upon the combinational arrangement of the perforations analyzed in the selected card column. The magnets 50 are individually designated by Roman numerals in Fig. 7 and referring to Fig. 3 it will be seen that the combinations of perforations are also designated by Roman numerals, it being clear that magnets 50 will be energized under control of the corresponding perforations.

In the present embodiment sorting operations are preferably carried out in a manner which is well known and fully shown and described in the U. S. patent to Michael Maul No. 2,025,602, to which reference may be had for a more complete description of the operation and construction of the machine. In order to more clearly understand the present invention, it is pointed out that the machine is provided with two sets of storing devices; one set being adjusted under control of the perforations, while in the same machine cycle a second set of storing devices controls the sorting mechanism in accordance with the analysis of the previous record. Between successive sorting cycles there is a transfer of the setting from the first named set of storing devices to the second named set of storing devices and after this transfer has been effected, the first set of storing devices is cleared out so as to be capable of being subsequently set under control of the next record analyzed. Obviously, after the second set of storing devices has controlled the operation of the sorting mechanism this set is cleared out so as to receive a subsequent transfer.

In more detail, each magnet 50, when energized, will attract its armature thereby releasing a related pawl 59 which thereupon is rocked in a clockwise direction so as to bring a shoulder thereof beneath one arm of a bell crank 52. The rocking of a bell crank 52 will, through the pawl 59, depress a bar 53 so as to rock an associated lever 54 whereupon the latter is latched by means

of a latching lever 55. Each lever 54 has connected thereto a contact operating bar 60 which, when depressed, closes certain contacts and opens other contacts. As is well known, the depression of certain of the bars 60 under control of the energization of related magnets 50 will effect the closure of contacts in combination so as to select an impulse transmitting line, some of which are represented in Fig. 7 by numerals and others of which are represented by letters. The selection of one of these lines will effect the sorting of a record card having a similar designation, as is well known in the art.

The rocking of the bell cranks 52 to cause the rocking of the levers 54 through bars 53 and pawls 59 is performed by means of a bar 51 which is rocked by its associated cam to the left, as shown in Fig. 7, and which cam is timed so as to effect the transfer from the first set of storing devices to the second set of storing devices at the desired time.

The clearing out of the setting on the first set of storing devices is performed by the rocking of a bar 56 to the right (Fig. 7) under control of its associated cam. This will unlatch the pawls 59 from the bell cranks 52. The clearing of the setting on the second named set of storing devices is effected by the rocking of a bar 58 to the right, as shown in Fig. 7, and the movement of the bar 58 in this direction is effected by the related cam 30 and rocks the pawls 55 to unlatch the levers 54.

As previously described the closure of contacts in combination will select one of a plurality of impulse transmitting lines and a line which corresponds to the designation on the card analyzed in the preceding sorting cycle. Since in the present instance, the designations on the record cards comprise a complete set of alphabetical characters, or 26 letters, as well as the ten digits, 36 impulse transmitting lines are necessary.

The plurality of impulse transmitting lines are divided into three sets; one set for the digits 0 to 9; another set for the letters A-N; and the third set for the letters N-Z, and coordinated with these three sets of lines are related impulse

emitters designated 66, 67 and 68 in Fig. 7. By means of suitable wire connections between the contact elements 36, 37 and 38 and impulse

emitters 66, 67 and 68, the positioning of the knob 33 will cause the electrical selection of one of these emitters. The emitters are of the usual form, that is, it includes a plurality of contact

points with which a brush makes successive electrical contact at the time the record to be sorted is successively coordinated with the sorting blades 26, Fig. 5. Obviously, since each impulse emitter will permit the sorting mechanism to be controlled by the related set of designations all of the records which bear other designations will be passed into the reject pocket "R", Fig. 5. In

Fig. 7, the complete wiring connections between the impulse transmitting lines leading from the translator contacts to the contact point of the respective emitters are not shown. However, the corresponding lines are similarly designated so as to make the connection of related lines apparent.

The transmission of an electrical impulse to the sorting magnet is effected by the following described circuit, which leads from the line side 70 through selected closed translator contacts to the selected impulse transmitting line, the related contact point of the associated emitter, to a contact element 36, 37 and 38, depending upon the position of the contact arm 34, to the segment 35, a relay magnet 39, the sorting control magnet

75

27, and to the other side of the line 80. The energization of the relay magnet 39 effects the closure of a stick circuit for the sorting magnet 27 through stick contacts 41 and cam controlled contacts 69.

5 To recapitulate, it will be seen that if the knob 33 is adjusted to effect the sorting of records bearing the numeral designations 0 to 9, and which position is shown in Fig. 7, it will be apparent that the emitter 66 will be selected. Therefore, sorting operation will be effected for records bearing such designations provided, of course, the card field selector switch 63 is set to the position shown in Fig. 7. In the event that 10 cards are imperforated in the lower card field such cards will be disposed in the reject pocket "R".

When the selector switch 63 is positioned so as to make contact with the lower contact point, cam operated contacts 64b (Fig. 7) will be operative so as to cause an operative relationship between the analyzing brushes 24 and the upper card field. It will be understood that the upper card field 15 may contain perforations representing 26 alphabetical characters, and since the machine is equipped with only 13 sorting pockets it is necessary to pass such records through the machine in two sorting runs. When the knob 33 is adjusted so that the contact 34 makes contact with the contact element 31 the impulse emitter 67 is selected for operation so that records bearing the 20 designations A-M will be sorted out, and records bearing other alphabetical designations will be disposed in the reject pocket. From what has been previously described it will be noted that 25 the positioning of the knob 33 to effect sorting operations for designations A-M will cause the positioning of the indicator plate 31 so that the corresponding designations will be simultaneously brought into view, and each associated with the 30 related sorting pocket. By bringing such designations into view, the operator will be able to quickly perceive into which sorting pockets records having certain designations are selectively disposed.

40 45 For sorting operations to sort records containing the designations N-Z the knob 33 is adjusted so that the contact arm 34 makes contact with the contact element 38 thereby selecting the impulse emitter 68 for sorting operations. The indicator plate 31 will, accordingly, receive an adjustment so as to bring the designations N-Z simultaneously into view so that the operator will know into which sorting pockets records having such designations will be disposed.

50 While the invention has been illustrated in connection with a sorting machine for sorting numerically and alphabetically designated records in three sorting runs, it is obvious that if a machine of this capacity is not required changes can easily be made so as to sort records by fewer sorting runs. For example, if it is desirable to sort records bearing only alphabetical designations in two sorting runs, only two impulse emitters 67 and 68 are necessary. In another form of machine having 26 sorting pockets all of the records bearing alphabetical designations will be sorted during a single run and if certain of these 55 records contain numerical designations the machine may be equipped with an impulse emitter 66 so as to effect the sorting of records in accordance with the numerical data in another sorting run. Each of the above types of machine may by

suitable alterations be equipped with the indicating device herein shown and described.

5 While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the 10 intention, therefore, to be limited only as indicated by the scope of the following claims.

What is claimed is:

1. In a machine for sorting records provided with designations capable of being analyzed for controlling sorting of the records selectively in a plurality of sorting pockets, and including a settable means which in its differently set position causes a sorting mechanism to be responsive to only a certain set of designations analyzed during each sorting run, whereby each sorting pocket 20 may receive in different sorting runs records bearing different designations, the combination of indicating means at each of said sorting pockets comprising means provided with indications corresponding to designations of records sorted in the related pockets and means at each sorting pocket associated with the related group of indications for selectively by different positions of the settable means rendering a particular indication 25 visible, and means for causing said settable means to control the indicating means to render visible for each position of the settable means indications corresponding to the particular designations of the records received by the sorting pockets in 30 the sorting run selected by the settable means.

2. The combination according to claim 1 in which the indicating means comprises a fixed cover plate for a bar connected to said settable means and extending longitudinally along the 40 45 sorting pockets, said bar carrying groups of characters associated with the sorting pockets, one of which characters is visible adjacent each sorting pocket through a window of said fixed cover plate depending upon the adjustment of the settable means.

3. In a machine for sorting records provided with designations capable of being analyzed for controlling sorting of the records selectively in a plurality of sorting pockets and including a settable means which in its differently set position causes the sorting mechanism to be responsive to only a certain set of designations analyzed during each sorting run, whereby each pocket may receive in different sorting runs records bearing different designations, the combination of an indicator comprising a bar extending longitudinally of the sorting machine and provided adjacent each sorting pocket with a plurality of characters representing the designations of records sorted 60 therein in the different sorting runs, a fixed cover plate extending over the bar and provided with a series of windows each window enabling only one character to be visible and dependent upon the position of the settable means, and means for operatively connecting said bar to said settable means to cause by each setting of the settable means the adjustment of said indicator bar to bring simultaneously into view a series of characters adjacent the plurality of pockets to designate the designations on the records sorted in the pockets in the sorting run selected by the settable means,

MICHAEL MAUL.
